UNITED STATES PATENT OFFICE.

OTTO STEIN, OF OSCHERSLEBEN/BODE, GERMANY.

PAINTER'S IMPLEMENT OR PATTERN.

Application filed June 20, 1927, Serial No. 200,225, and in Germany June 29, 1926.

This invention relates to an improved painters' implement or pattern for producing imitations of Gobelins or tissue designs herewith, comprising an outer rectangular frame and parallel longitudinal stays which consist of cane strips having convex contact surfaces, so that the longitudinal edges of the strips do not rest against the wall but remain a short distance therefrom, whereby a smearing of the color on the painted wall is prevented as only sharply defined lines are obtained. Said improved implements being illustrated on the accompanying drawing, in which—

15 Figs. 1 and 2 are respectively a plan view of part, and a longitudinal section, of one appropriate constructional form of the same, while Fig. 3 is a fragmentary side view thereof on a larger scale;

20 Figs. 4 and 5 are similar views to Figs. 1 and 2 of a modification of the implement, while

Fig. 6 shows part of Fig. 5 on a larger scale with a further modification thereof, and

25 Fig. 7 is a plan view of part of a further constructional form of the implement.

Referring to Figs. 1 to 3: The improved implement or pattern comprises a rectangular tubular frame *a* carrying in gratalike manner a plurality of parallel longitudinal cane strips *c* extending over its whole length and forming uninterrupted spaces *b* between them which serve for painting the desired parallel lines on a wall painting. The thickness of said cane strips, as well as their distance from one another, can be any desired one to suit the actual design to be painted. Said cane strips *c* have convex outer contact surfaces with which they are placed upon the wall to be painted, whereby its longitudinal edges do not touch the wall but are spaced apart therefrom so that a

neat painting without any blotting is attained.

45 Said cane strips *c* are preferably threaded in one piece by being passed through corresponding holes *d*, *e* in the lateral members of the frame *a*.

Figs. 4 and 5 show, instead of a tubular, 50 a plate-like frame *a'* having one strengthening rib *a''* or two such ribs *a''* (Fig. 6), the other arrangement of the cane strips *c* threaded in gratalike manner through holes *d'*, *e'* in the lateral frame members and 55 forming uninterrupted spaces *b'* between them being similar to that afore described.

As shown in Fig. 7, the pattern may also be punched out of a sheet-metal plate in gratalike manner so as to form an outer 60 rectangular frame *a³* with longitudinal stays *c³* forming uninterrupted spaces *b³* between them.

The imitation of the Gobelin or tissue design with the aid of the improved implement 65 or pattern is produced by first painting any picture or design on the wall and then painting weakly over said picture the uninterrupted parallel lines of the Gobelin or tissue design, which lines can be placed in any 70 desired directions, with the aid of said implement, while particularly favourable colour effects can be attained by using two or more of such patterns with differently spaced cane strips.

75 What I claim, is:—

An implement or pattern for painting imitations of Gobelins and tissue designs, comprising an outer rectangular frame, and parallel longitudinal stays which consist of 80 cane strips threaded in one piece through the lateral frame members, said cane strips having convex outer contact surfaces.

In testimony whereof I have hereunto set my hand.

OTTO STEIN.
